UNITED STATES PATENT OFFICE.

JOHN T. LYONS, OF PAWTUCKET, RHODE ISLAND.

UNION UNDERGARMENT.

1,189,270.

Specification of Letters Patent.

Patented July 4, 1916.

Application filed October 9, 1915. Serial No. 55,098.

To all whom it may concern:

Be it known that I, JOHN T. LYONS, a citizen of the United States, and resident of Pawtucket, county of Providence, State 5 of Rhode Island, have invented an Improvement in Union Undergarments, of which the following description, in connection with the accompanying drawing, is a specification, like characters on the drawing 10 representing like parts.

This invention relates to improvements in woven or knitted union suit undergarments, either of the closed or open crotch type adapted for men, boys, women, or children.

The principal objects of the invention are to provide a garment having a minimum number of seams and gussets and having a single opening to permit the garment to be 20 put on the wearer with a minimum number of fastenings to retain the garment in smoothly closed position.

The usual forms of union suits are provided with a front extending from the collar to a point below the waist line or in some instances to the crotch, and one or more back openings extending from the crotch approximately to the waist line with inserts such as gussets and 30 flaps secured to the edge of the sections of the back and adapted to overlap to insure complete closure of the opening. These gussets and flaps are connected to the body of the garment by a transverse seam located 35 at or adjacent to the waist line.

The binding of the edges of the sections of the garment along the front and rear openings with the buttons required to insure the closure of the openings not only 40 renders the production of the garment expensive but causes the garment frequently to need repairs because of the tension placed upon the closure and seams during wear and the injuries sustained by the garment 45 during laundrying.

The presence of an opening in the front of the garment is objectionable to the wearer for the reason that when thin shirts are used the overlapping portions and buttons are plainly visible and when stiff bosom shirts are worn the buttons frequently interfere with the smooth setting of the shirt.

The presence of numerous buttons upon

the back of the garment is likewise objectionable as are also the seams across the back which frequently give way or if improperly positioned result in an uncomfortable misfitting garment. By the present invention the front opening is entirely 55 omitted and a single opening provided in the back which permits the garment to be readily put on, a single suitable gusset and flap being provided to insure the closure of the opening when upon the wearer. 60 This gusset and flap is so constructed that a button or other suitable attachment on or near the collar, conveniently accessible to the wearer, suffices to retain the garment in closed position, but it will be understood 65 that other fastenings may also be provided if desired.

In the preferred embodiments of the invention the button at the collar is at the center of the back so that it lies near the 70 concaved portion of the body which follows the spinal column and consequently is practically free from contact with the body or with the overlying apparel. In case an additional fastening is desired a button may 75 be placed below or adjacent the waist line in such position that its presence will not be noticeable to the wearer.

I am aware that heretofore union suits have been made with a front opening by 80 means of which the garment may be put on, the gussets being so arranged within the opening that the same may be closed by a single button at the collar but this form of garment is inconvenient in that the multiplicity of thicknesses lie across the chest of 85 the wearer and as before stated the edges of the sections of the garment are visible through thin shirts. Such garments however are provided in the back with the 90 usual gussets and flaps above described which are seamed through the garment transversely along the waist line and are 95 secured to the edges as aforesaid.

The drawing herein illustrates a preferred 100 embodiment of my invention in which,

Figure 1 is a front elevation of a closed crotch union suit, and Fig. 2 is a rear elevation of the same showing the gusset and flap in closed position.

The drawing illustrates a closed crotch union suit which comprises a body portion 1 having integral leg portions 2 and a trans-

verse gusset 3, which preferably is of elastic material, extending across the crotch portion.

The garment may be provided with short sleeves 4 as indicated herein or with long sleeves or made in athletic type with no sleeves as is usual in summer and winter types of undergarments. The collar 5 preferably is constructed to fit loosely the neck of the wearer but in this type of garment is of such size that the garment cannot be put on through the neck opening as is the case with certain types of low neck garments.

15 The front portion 6 of the body of the garment is plain and uninterrupted by openings or seams of any character from the collar to a substantial distance below the waist line and the leg portions 2 preferably constitute integral continuations thereof. Garments of this character can be woven upon a loom or knitted upon either a circular knitting machine or upon a flat knitting machine without the necessity of special mechanism. The back of the body portion is so constructed that when slit the adjacent portions present a fullness of decreasing extent from the crotch toward the collar, the portions having the fullness aforesaid being 20 constructed in the completed garments to overlap and form a complete closure when the garment is upon the wearer.

25 The back of the garment preferably is slit vertically from the collar to the crotch or to the seam of the thigh portion of one of the legs and a gusset 7 which is cut on the bias to give elasticity is secured preferably by an elastic seam 8 to the edge of one of the sections 9 of the back of the garment, 30 the gusset 7 being of sufficient width to extend a considerable distance beyond the vertical median line connecting the collar with the crotch. The gusset 7 is preferably provided with greater fullness both longitudinally and laterally than the section of the garment to which it is attached. The fullness preferably is of decreasing amount extending from the crotch toward the collar.

35 In order to insure complete closure of the garment a flap 10 is attached to the edge 11 of the opposite section 12 of the back of the garment and may extend to or below the crotch. This flap like the gusset preferably is of greater fullness than the section of the 40 garment to which it is attached and in closed crotch suits the fullness of this complementary flap like that of the gusset preferably is of decreasing fullness from the crotch toward the collar and preferably is joined to 45 the gusset at the crotch. Where, as illustrated herein the union garment is provided with a transverse crotch closing gusset 3, the lower edges 14, 15, of the gusset and the flap may be secured directly to the edge of 50 the gusset 3, thus extending downward from

the leg portion to a point 13 upon the thigh, as illustrated in Fig. 2.

The elasticity of the longitudinal seams which connect the gusset 7 and flap 10 respectively with the edges of the section of the back tends to assist in drawing the back portions of the garment into proper position when the members of the back have been spread apart, since these seams, when the lower portion of the back is open, extend along the arched portion of the back of the wearer and are stretched to a considerable extent and when the strain is relieved tend promptly to return to their normal position, thus forcing the flap and gusset into normal closed position.

55 In the garment constructed as aforesaid a single button 16 located on or near the collar of the garment is sufficient to retain the parts in proper position but in order to provide against an emergency occasioned by the loss of the button a button-hole 17 may be provided on the under part of the garment to receive an ordinary collar button. While the single button above referred to is usually sufficient to retain the garment in closed position one or more additional fastenings between the collar and hip portion may be provided. As illustrated herein a single button 18 is placed at a point below the waist line so that the button will lie within the curved portion of the body of the wearer where the waist merges into the hip so that no inconvenience will be caused to the wearer by pressure against the button. By thus providing the opening in the back extending from the collar or shoulder to or below the crotch the garment may be easily slipped on and quickly closed by the button at the collar and the security of the closure may be insured by the single button adjacent the hip portion.

60 It will be observed that the double thickness of material formed by the overlapping of the flap and gusset will lie along the hollow portion of the back of the wearer so that the presence of this additional thickness will not interfere with the proper fitting of the overlying apparel and will not be noticed by the wearer. Furthermore the presence of this double thickness adds to the comfort of the garment, particularly in cold weather by reason of the fact that it provides an increased protection for the spine. In hot weather this additional thickness of material 65 prevents the sudden chilling of the back and is thus adapted to prevent colds and rheumatism.

65 It is to be understood that the particular embodiment of the invention described herein is illustrative merely but is not restrictive and that the opening in the back may be located otherwise than in the median line connecting the collar with the crotch and that my invention is intended to cover broadly any 70

form of union suit having a single opening located in the back with means for insuring the closure of the garment and for retaining the same normally in closed position. It is also to be understood that while I have defined the opening as extending from the collar to the crotch this position of the opening is not restrictive and that an opening extending from the collar or the shoulder to the crotch or to a point adjacent to, either above or below the median line of the crotch is within the meaning of the claims hereto annexed and that the term "button" is used in a general sense to cover any usual type of fastening.

Having thus described my invention, what I claim as new and desire to secure by Letters Patent is:

1. A union garment comprising integral body and leg portions having a front permanently closed from the neck to a substantial distance below the waist line and a back divided from the collar to a point on the thigh, one portion of the back being formed of a fullness of decreasing extent from the crotch toward the collar and the opposite portion having a flap of like decreasing fullness secured to its edge and arranged to overlap the complementary portion of the back and fastening means for said back arranged at the collar and adjacent the waist line, the arrangement of the garment being such as to permit the fitting

to or removing from the person without releasing the fastening means at the waist portion. 35

2. A union garment comprising knitted integral body and leg portions, the body portion having a front permanently closed from the neck to a substantial distance below the waist-line, the back having a single opening extending vertically from the crotch to the collar, overlapping flap and gusset portions elastically seamed respectively to the adjacent edges of the back portion, said gusset and flap being of greater fullness than the sections to which they are secured and means located at the collar for securing the flap in overlapped position. 40 45

3. A union garment comprising integral body and leg portions, the body portion having a front permanently closed from the neck to a substantial distance below the waist-line and a back divided from the collar to a point on the thigh, overlapping flap and gusset portions secured to the adjacent edges of the back, the fabric of said gusset and flap portions being bias to the fabric of the body portions and provided with greater fullness than that of the body portion and means for securing the back portions together at the top. 50 55 60

In testimony whereof, I have signed my name to this specification.

JOHN T. LYONS
